UNITED STATES PATENT OFFICE.

IRWIN M. THOMPSON, OF BANNISTER, LOUISIANA.

BALE-TIE.

1,130,551.

Specification of Letters Patent.

Patented Mar. 2, 1915.

Application filed October 25, 1913. Serial No. 797,200.

To all whom it may concern:

Be it known that I, IRWIN M. THOMPSON, a citizen of the United States, and a resident of Bannister, in the parish of Beauregard and State of Louisiana, have invented a new and Improved Bale-Tie, of which the following is a full, clear, and exact description.

This invention relates to improvements in bale ties, and has for an object to provide an improved structure which when placed in position will become locked to the bale.

Another object of the invention is to provide a bale tie with a spur having a hooked portion which when driven into place will interlock with the remaining parts so that the spur cannot work loose.

A still further object of the invention is the provision of a buckle with an interlocking spur arranged to extend at an angle, whereby the bar on the binding wire will tend to hold the spur in place and consequently hold the buckle against shifting from one position to another.

In carrying out the object of the invention the tie or buckle is formed from a single blank stamped out of sheet metal. The blank is formed with a pair of apertures for one end of the tie wire, and with an elongated aperture through which the spur is passed when applying the buckle to a bale. Arranged adjacent the elongated opening or aperture is a comparatively narrow bar which is adapted to spring to one side as the spur is driven into place, and to again spring back over the hook or extension on the spur, whereby the spur is locked against removal.

In the accompanying drawing—Figure 1 is a perspective view of a buckle applied, the same embodying certain features of the invention; Fig. 2 is a top plan view of the buckle shown in Fig. 1; Fig. 3 is a blank of the buckle shown in Fig. 2; Fig. 4 is a section through Fig. 2 approximately on line 4—4; Fig. 5 is a perspective view of a slightly modified form of buckle to that shown in Fig. 2; Fig. 6 is a blank of the buckle shown in Fig. 5.

Referring to the accompanying drawing by numerals 1 indicates a bale of any desired kind to which the buckle or tie 2 is connected. The tie 2 is associated with a binding member or wire 3 which encircles the bale 1 in the usual manner, and is connected with the tie or buckle 2.

Buckle or tie 2 is formed with a body 4 bent at 5 so as to have an end member 6 and a top member 7. The end member 6 is provided with an aperture 8, and the top member 7 is provided with apertures 9 and 10, aperture 10 having a notch 11 extending downwardly into end 6 so as to better pinch the end of the wire 3, as shown in Fig. 1. In forming the notch or aperture 9 the same is elongated and extends at an angle to the tie so as to present a spring bar 12 comparatively narrow, and being formed of metal will spring to one side as the spur 13 is driven into bale 1. The spur 13 is provided with a hook or shoulder 14 which is designed to snap beneath bar 12, as shown in Figs. 2 and 4, when the spur has been driven into the bale 1. Spur 13 is the extreme end of the extension 15 and bent on line 16 while extension 15 is bent on line 17 so that the extension will extend at an angle to the general direction of the blank. This arrangement of the extension at an angle, as shown in Figs. 1 and 2, is of advantage in that it causes the strain to firmly hold shoulder 14 beneath bar 12, and thereby positively prevents the spur from becoming disengaged from bale 1.

In Figs. 5 and 6 will be seen a slightly modified form of the invention in which the blank 4' is bent at one end for forming an end member 6' having an aperture 8 and a notch 11 which merges into a central slot 18 extending longitudinally of the body of the blank. The aperture 18 merges into a pair of small notches 19 and 20 having therebetween a tongue 21 formed with a spur 22 having a shoulder 23. From Fig. 6 it will be observed that in stamping out the tongue 21 an extension 24 is also formed, which extension is designed to receive the shoulder 23 after the spur 22 has been driven into the bale, tongue 21 being sufficiently resilient to allow this action. The side of the blank is somewhat resilient and will give laterally, slightly, so that after the shoulder 23 has passed the extension 24 the extension 24 will snap over the shoulder 23 and lock the shoulder against movement.

What I claim is:

1. A bale tie formed with a body portion having an aperture therein, near one edge, and with an extension formed with a spur on the extreme end, said spur having a shoulder, said extension being bent at an angle so that said spur may be driven

through said aperture, and said shoulder overlap said body.

2. A bale tie comprising a body formed with an aperture therein, and a tongue extending from near one end of said body, said tongue having a shoulder or hooked portion, said shoulder being designed to be passed through said aperture, said tongue extending in such a direction as to cause 10 said shoulder to overlap part of said body, the tongue and body being sufficiently resilient for causing the shoulder to snap past the body and interlock therewith when in operative position.
- 15 3. A bale tie comprising a body formed with an aperture for receiving a tie wire and with a resilient bar, said body having an

extension formed with a spur, said spur being formed with a shoulder over which said bar is adapted to move when the spur is 20 driven into position, said extension being bent at an angle to the general direction of said body whereby, when said tie wire is engaged therewith on the side of the shoulder, the pull of the wire will give said extension a tendency to press said shoulder beneath said bar. 25

In testimony whereof I have signed my name to this specification in the presence of two subscribing witnesses.

IRWIN M. THOMPSON.
